Primary Examiner — Christy Nemeth(74) *Attorney, Agent, or Firm* — FisherBroyles, LLP;
Susan M. Oiler(57) **CLAIM**

The ornamental design for a battery container, as shown and described.

DESCRIPTION

FIG. 1 is a perspective view of a battery container;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The dash-dash broken lines are for the purpose of illustrating environmental subject matter that forms no part of the claimed design. The dot-dash broken lines are for the purpose of illustrating a boundary, and form no part of the claimed design.
